TOOL FOR CLEANING HYPODERMIC SYRINGES OR THE LIKE

John Robert Lend, 5247 W. North Ave., Chicago, Ill.

Filed Mar. 29, 1962, Ser. No. 69,492

Term of patent 14 years

(Cl. D9—2)

FIG. 1 is a side elevational view of a tool for cleaning hypodermic syringes or the like showing my new design;

FIG. 2 is a fragmentary side elevational view of the upper portion thereof viewed at 90° to FIG. 1;

FIG. 3 is an enlarged top view of the tool;

FIG. 4 is a cross sectional view taken substantially along the plane of the line 4—4 in FIG. 1;

FIG. 5 is a fragmentary enlarged vertical cross sectional view taken through the top end of the tool substantially as viewed along the line 5—5 in FIG. 3;

FIG. 6 is another similar vertical cross sectional view taken at right angles to the FIG. 5 view and substantially as viewed along the line 6—6 as shown in FIG. 3.

The dominant features of my design reside in the portions shown in full lines.

The side of the tool that is opposite that shown in FIG. 1 is substantially the same in appearance and the side opposite that shown in FIG. 2 is substantially plain.

I claim:

The ornamental design for a tool for cleaning hypodermic syringes or the like, substantially as shown and described.
